UNITED STATES PATENT OFFICE.

GEORGE K. SCHLÖTTERER, OF CHESTER, PENNSYLVANIA, ASSIGNOR TO HARBISON-WALKER REFRactories COMPANY, OF PITTSBURGH, PENNSYLVANIA, A CORPORATION OF PENNSYLVANIA.

INSULATED FIRE BOX.

Application filed June 26, 1925. Serial No. 39,792.

This invention relates to brick kilns. More particularly it relates to a seal for the fire boxes of downdraft brick kilns.

The object of the invention is to render the walls of fire boxes of brick kilns impervious to passage of air or gases of combustion therethrough.

Referring to the drawings Fig. 1 is a partial central vertical section through a standard type of brick kiln and one of the fire boxes usually associated with such kilns; Fig. 2 is a partial horizontal section on the line II—II of Fig. 1; Fig. 3 is a horizontal section through one of the fire boxes on the line III—III of Fig. 4; Fig. 4 is a central vertical section through one of the fire boxes on the line IV—IV of Fig. 3; and Fig. 5 is a central vertical section at right angles to the section of Fig. 4, taken on the line V—V of Fig. 3.

Kilns for burning bricks are usually circular, with a plurality of fire boxes built into the walls, with openings for firing from the outside of the kiln, and with means for 25 the gases of combustion to pass upward from the fire box toward the top of the kiln, and means for supplying air either by forced draft or induced draft underneath the grate bars of the fire box, and means to 30 draw off the hot gases through the bottom of the kiln. These structures are known as downdraft kilns.

It has been found that the bricks being burned positioned nearest to the inner walls 35 of the fire boxes in such kilns are frequently discolored and under or overburned. This is due to the passage into the kiln from the fireboxes of air, or unburned fuel gases, or both, through crevices in the inner wall of 40 the fire box, thus cooling the bricks adjacent thereto, or else overheating them, according to the particular form of leakage 45 that takes place. The present invention has for its object the prevention of such leakage through the fire box wall into the kiln.

Referring to the drawings, and particularly to Fig. 1 a standard form of downdraft kiln is shown comprising a floor 1, an outer wall 2, and a top 3. A fire box is illustrated in section in this figure, and it 50 comprises an air inlet 4, controlled by a door 5, leading into an ashpit 6, above which are transverse grate bars 7, adapted to sup-

port fuel in the combustion chamber 8. A door 9 controls a passage 10 through which fuel may be passed into the combustion chamber 8. A checker-work 11 is provided above the combustion chamber, and through it hot gases pass upward into the kiln, towards the top thereof, and then are drawn off through flue passages 12 in the floor, which extend radially from a central well connected by a flue 13 to a stack 14 outside the kiln. Openings 15 are provided in the floor, leading down into the passages 12, through which the hot gases are drawn off after having passed upward into the kiln and downward around the bricks being burned, as will be thoroughly understood by those familiar with this art.

In Figs. 3, 4 and 5 a supplementary air supply pipe 16 is shown, and this may be used for a forced draft system in which air under pressure is supplied beneath the grate bars 7. The particular method of supplying air for combustion is not a part of this invention, which is applicable to forced draft, induced draft, or to natural draft. It will, however, be understood that in forced or induced draft there is a greater tendency toward leakage of air from the fire box directly into the kiln. This tendency increases as the walls of the fire box become cracked by repeated heating and cooling in use, as will be readily understood.

The present invention consists in dividing the three inner walls of the fire box into separate portions 20, and 21, with an intermediate space 22 extending coextensive 90 with the inner walls of the fire box, as clearly shown in Figs. 2 and 3. Near the top the space 22 is partially closed, leaving feed openings 23 extending to the top of the walls 20 and 21. See Fig. 2.

The space 22 around the inner wall of the firebox is filled with sand, or other similar finely powdered, non-inflammable, close-packing material, as illustrated in Figs. 1, 4 and 5.

It has been found that this seal in the wall of the fire box prevents leakage of gas or air therethrough into the brick kiln, and therefore prevents the spoiling or unequal burning of a material number of bricks immediately adjacent to the fire boxes, in the burning process. It also results in bricks of uniform coloring being made, and has

very distinct advantages in the operation of this kiln. In addition a material saving of fuel results. It has been found with the firebox walls sealed or insulated in this way 5 that a charge of bricks can be burned in materially less time and with materially less fuel than with uninsulated, or unsealed fireboxes. In addition, bricks adjacent the fireboxes that were formerly damaged are 10 now burned uniformly with those in other parts of the kiln.

The sand may be replenished through the openings 23, as it becomes packed down, or as it is dissipated into the cracks or crevices 15 that develop in the fire box walls. Material non-granular in form might be equally efficient as a seal or insulator for a time, but granular material is preferred because it is self-conforming to the space to be filled, it 20 readily flows into any new cracks or holes that develop, and as a body it cannot itself develop cracks or holes due to expansion and contraction due to changes of temperature. I prefer sand because it is universally available, cheap, dense and non-caking 25 as well as heat resistant within the temperatures here involved.

I claim:—

1. A firebox construction comprising an 30 inner and an outer firebox wall with a space between, said space being filled with pow-

dered non-inflammable material for the prevention of escape of gases through the wall.

2. A firebox construction for brick kilns, comprising an inner and an outer firebox 35 wall with a space between, said space being filled with sand for the prevention of escape of gases through the wall.

3. In a brick kiln comprising a firebox built into the wall thereof, a seal for insulating the fire box from the main chamber of the kiln, comprising a vertical body 40 of sand positioned in the wall of the firebox.

4. In a brick kiln comprising a firebox built into the wall thereof, a seal for insulating the firebox from the main chamber of the kiln, comprising a vertical body of finely divided non-inflammable material 45 positioned in the wall of the fire box.

5. A firebox for brick kilns, comprising a 50 combustion chamber, a lateral wall separating said chamber from the interior of the kiln, said wall being vertically divided to form an intermediate space partially surrounding the combustion chamber, said 55 space being filled with dry powdered material adapted to prevent passage of gas from the firebox to the interior of the kiln through the lateral walls of the firebox.

In testimony whereof, I sign my name. 60

GEORGE K. SCHLÖTTERER.
